UNITED STATES PATENT OFFICE.

RICHARD W. BOCK, OF RIVER FOREST, ILLINOIS.

DESIGN FOR A LAMP.

Application filed February 2, 1925. Serial No. 12,238. Term of patent 3½ years.

To all whom it may concern:

Be it known that I, RICHARD W. BOCK, a citizen of the United States, residing at River Forest, in the county of Cook and State of Illinois, have invented a new, original and ornamental Design for Lamps, of which the following is a specification, reference being had to the accompanying drawing, forming part thereof.

The figure is an elevational view of an ornamental lamp made of such material as plaster of Paris, showing my new design intended to simulate a Christmas tree.

I claim:

The ornamental design for a lamp, as shown.

RICHARD W. BOCK.
